UNITED STATES PATENT OFFICE.

ALCIDE E. BEAUDETT, OF ALBUQUERQUE, NEW MEXICO.

AEROPLANE.

1,023,000.

Specification of Letters Patent.

Patented Apr. 9, 1912.

Application filed September 6, 1911. Serial No. 647,895.

To all whom it may concern:

Be it known that I, ALCIDE E. BEAUDETT, a citizen of the United States, and a resident of Albuquerque, in the county of Bernalillo 5 and State of New Mexico, have invented a new and Improved Aeroplane, of which the following is a full, clear, and exact description.

My invention relates to an improvement 10 in aeroplanes, and has for its object the provision of a simple, inexpensive but efficient device for absorbing and eliminating the shock when alighting.

In the drawings:—Figure 1 is a front elevation of the improvement; Fig. 2 is a partial side view; and Fig. 3 is a vertical section of the cylinder.

The present embodiment of the invention is shown applied to the frame 1 of an aeroplane, and comprises a plurality of wheels 2, which may be pneumatic tired as shown, and are journaled on axles 3. Each of the axles is held in bearings 4 on a pair of arms 5, and each arm is provided with a ring 6 at 20 its other end which engages over a spindle 7 at the adjacent end of a shaft 8 arranged transversely of the frame. The shaft 8 is arched at 9, at its center and a bar 10 is provided with a bearing 11 engaging the inner end of each spindle adjacent to the arm. Each bar is braced laterally by a brace 12 having one end bolted to the top of the bar as indicated at 14 and the other end provided with a bearing 13 engaging the outer 30 end of the adjacent spindle. The spindle is engaged by nuts 15 outside of the bearing 13, and the bars 10 are connected near the shaft by a cross bar 16. A cross plate 17 is arranged near the tops of bars 10, and a brace 40 rod 18 connects each end of the plate with the adjacent bar 10. The said rod passes through the plate at its upper end, and nuts 19 are threaded onto the said rod above and below the plate. Brace rods 20 are arranged 45 between the bars 10 and the braces 12, each rod 20 having a bearing ring 21 encircling the brace, near its lower end. The braces 12 are forked at their lower ends and the arms of the fork engage over the spindle adjacent to the outermost arm 5.

An eye bolt 22 is arranged at each end of plate 17, and a cylinder 23 is connected with each bolt, each cylinder being provided with spaced lugs 24 at its upper end for engaging the eye of the bolt, and a bolt 25 is passed through the lugs and the eye for

pivots connecting the cylinder to the eye bolt.

Each cylinder, Fig. 3, is provided with an upper head 26 secured in place by any suitable means, and a lower head 27 held in place by screws 28. The lugs 24 are connected to a plate or button 29, having a stem 30 which is passed through an opening in the head 26 and is headed to hold the plate 60 or button in place. Each cylinder is provided with a vent 31, near its upper end and a plunger composed of three spaced heads 32, 33 and 34 is arranged in the cylinders. Each head is composed of a disk of 65 leather 35 or the like held between two disks 36 and 37 of metal. The disks 37 fit the cylinder, and the disk 35 is of larger diameter so that the disk is cupped, and a flange 38 is provided, and the disks 36 fit within the 70 cup or flange. The upper disk of the head 32 is provided with a central opening, through which extends a stem 39 which is headed below the disk. The stem extends into a block 40 of rubber or like flexible material and is secured to the block by a pin 41. The block is adapted to engage the head 26 when the plunger moves upward to cushion the plunger. Bolts 42 having heads 43 are passed through the three heads of the 75 plunger from below upward and nuts 44 are threaded onto the bolts above the heads. Spacing sleeves 45 are provided for holding the heads in spaced relation, and a tube 46 is connected with each bolt 42. Each tube 80 extends through an opening in the head 27, and the end thereof fits over the head 43 of a bolt 42. The tubes extend downward, and the lower end of each tube is provided with a bearing 47 engaging the adjacent end 85 of the adjacent axle 3. The tubes of each cylinder are connected at intervals by rings or loops 48, and each tube is bent laterally above the wheel 2 to its connection with the axle. The vent 31 is of small size with 90 respect to the diameter of the cylinder so that sufficient resistance is offered to the upward movement of the plunger to properly cushion the frame from the shock of the 95 wheels striking the ground.

105

The arms 5 permit the wheels to move upward, as shown by dotted lines in Fig. 2, the arms swinging on the shaft 8.

The operation of the device will be obvious from the description. The air in the 110 cylinders slows the upward movement of the plungers, and the greater the shock the more

resistance is offered by the air. Should the plunger strike the top of the cylinder, the block 40 would prevent any damage to the mechanism.

- 5 The cylinders are connected by a tube 49, each end of the tube engaging a vent 31 of a cylinder.

I claim:—

1. In combination with the frame of an aeroplane, of a shaft on the frame, spaced pairs of arms having bearings at one end engaging the ends of the shaft, an axle connected with the other ends of each pair of arms, a wheel on each axle, an upright supported by the shaft, at the inner side of each pair of arms, a brace between the top of each upright and the shaft at the outer side of the arms, a cross plate near the tops of the uprights, a cylinder pivoted at its upper end to each end of the cross plate, a tube pivoted to each end of each axle and extending into the adjacent cylinder, a plunger in each cylinder to which the tubes are connected, each cylinder having a vent opening 20 above the plunger and a tube connecting the cylinders, the ends of the tube communicating with the vent openings of the cylinders.
2. In an aeroplane, the combination with

the frame, of a shaft arranged transversely thereof, a pair of arms mounted to swing on each end of the shaft, a wheel journaled between each pair of arms, a cross plate above the shaft, a cylinder supported at each end of the cross plate, a plunger in the cylinder, and a rigid connection between each wheel and the plunger, each cylinder having a vent opening above the plunger, a cushion of rubber on the upper end of each plunger, and a connection between the vent openings of the cylinders.

3. In an aeroplane, the combination with the frame, of a shaft arranged transversely thereof, a pair of arms mounted to swing on each of the shaft, a wheel journaled between each end of the shaft, a wheel journaled between each pair of arms, a cylinder connected with the frame above each wheel, a plunger in each cylinder, a rigid connection between each wheel and the plunger of the adjacent cylinder, and a communication 45 between the cylinders for equalizing the pressure therein.
